BENJAMIN TATHAM AND JOSEPH STEGER, OF NEW YORK, N. Y.

Letters Patent No. 91,181, dated June 8, 1869.

IMPROVED RAILWAY-CAR BRAKE.

The Schedule referred to in these Letters Patent and making part of the same.

To all whom it may concern:

Be it known that we, BENJAMIN TATHAM and JOSEPH STEGER, both of the city, county, and State of New York, have invented a new and useful Improvement in Car-Brakes; and we do hereby declare the following to be a full, clear, and exact description thereof, which will enable those skilled in the art to make and use the same, reference being had to the accompanying drawing, forming part of this specification, in which drawing—

Figure 1 represents a longitudinal vertical section of this invention.

Figure 2 is an inverted plan thereof.

Figure 3 is a perspective view of the principal working-parts.

Figure 4 is a detached sectional view of the take-up.

Figure 5 is an inverted plan of a car, showing a modification of the connection between our double-wedge-shaped plate, and the brakes.

Similar letters indicate corresponding parts.

This invention relates to that class of car-brakes for which Letters Patent were granted to Joseph Steger, October 27, 1868, No. 83,418.

Our present improvement consists—

First, in giving to the friction-plate, which forms the principal feature of the above-named patent, an increased thickness from the centre towards its ends, in such a manner, that by the action of said friction-plate itself, the slack of the brake-chain or rope is taken up, if the cars are close-coupled, and thereby the effect of said friction-plate on the brakes is materially improved.

Second, in the arrangement of a rigid connection between the friction-plate and the upright reversing-lever, which connects with the brakes in such a manner, that if the car runs in one direction, the friction-plate acts by pushing, and when the car runs in the opposite direction, said friction-plate operates by pulling on the arm of the reversing-lever, and the effect of the friction-plate on the brakes is the same, in whatever direction the car moves.

Third, in the arrangement of a self-acting take-up, in combination with the brake-chain or rope, and with the couplings of the cars, in such a manner that when the cars run close together, the slack of the brake-chain or rope is taken up automatically, and when the cars separate, the slack is given out again, and thereby said brake-chain or rope is always kept in the proper condition to act on the brakes throughout the entire length of the train.

A represents the platform of a railroad-car, which is supported by two trucks B B, each of which runs on two pairs of wheels, D, mounted on the axles C*, in the usual manner.

To one of these trucks is secured a lever, E, which has its fulcrum on a pivot, a, secured in the end of

an arm, F, which is rigidly attached to the truck-frame, as shown in fig. 1.

The loose end of said lever is armed with a roller, b, and it is suspended upon the brake-rope or chain G, which extends throughout the entire length of the train, and which passes over rollers c, secured to the truck-frames of the several cars, and under the rollers b of the several levers E, as shown, its rear end being secured to the last car, and its front end to a windlass on the engineer's stand, or in any position convenient of access for the engineer, or for a brakeman charged with the particular duty of attending to the brakes.

The lever E extends under the axle C*, and it carries a roller, d, which acts against a corresponding roller, e, mounted on the axle. Between those two rollers, d and e, is situated the friction-plate or bar H, and this plate is made increasing in thickness from the centre towards the ends, as clearly shown in figs. 1 and 3. If the brakes are to be applied, the engineer or brakeman winds up or pulls on the brake-chain or rope G, and the friction-plates H, of the several cars, are squeezed tight between the rollers d and e, of their respective levers and axles, and as said plates are made to move between these rollers, the brake-rope or chain is kept taut by the wedge-shape of said friction-plate or bar, and the brakes are instantaneously pressed up against the peripheries of their respective wheels with the required force.

The connection between the friction-bar or plate H, and brakes, is effected by means of a reversing-lever, I, which is secured to the upper end of a vertical shaft, J, from the lower end of which extends an arm f, which is pivoted to the end of the friction-bar or plate, best seen in figs. 1 and 3.

The reversing-lever I, is double-armed, and each arm thereof connects, by rods g g', and links h h', and rods, m m', with levers i i', which are pivoted to the brake-heads k k', at the opposite ends of the car.

Each of these levers is double-armed, and its lower end connects, by a rod, l or l', with the brake-head k* or k**, at the opposite or inner end of the corresponding truck. If the car moves in the direction of the arrow 2, marked thereon in fig. 2, and a strain is exerted on the brake-chain or rope G, the friction-bar H is caused to move in the direction opposite to that in which the car moves, and the lever I is turned in the direction of arrow 1, and all the brakes are drawn up against the peripheries of the wheels, and if the car moves in the opposite direction of arrow 2, the friction-plate moves in the direction of arrow 3, and the lever I is turned in the direction opposite to the arrow 1, causing the brakes to be applied the same as before. As the friction-plate or bar is drawn in between the rollers d e, an additional strain is imparted to the brake-rope G, by the increasing thickness of said plate towards its ends, and the brakes are drawn

up tight against the wheels, and any slack existing in the brake-rope is taken up automatically.

It is obvious that this feature of our present invention is applicable to the form of reversing-levers described in our patent of October 27, 1868, No. 83,422, by connecting the friction-bar directly to one of the reversing-levers, as shown in fig. 5, of the drawing, so that the same is actuated by pulling and by pushing. In this case, the connecting-rods of the reversing-levers will be crossed to facilitate the operation in turning curves. By connecting the reversing-lever I to the windlass L, the brakes of each car can be applied by hand in the usual manner.

If the cars are not close-coupled, the amount of slack of the brake-rope or chain becomes such that the wedge-shaped plate or bar H will not be able to counteract the same, and in this case we apply the automatic take-up M, which consists of a head, m, mounted on the end of a shaft, n, and carrying two rollers, o, over and between which the brake-rope or chain is passed, as shown in figs. 1, 2, and 4.

On the shaft n is wound a rope, o', which connects with the end of a spring, p, wound on the stem of the buffer or coupling N. If the cars run close together, the buffer N is pressed in, and the head m is turned in the direction of arrow 4, figs. 1 and 4, and thereby

the slack of the brake-rope is taken up. If the cars separate again, as far as the coupling will permit, the head m turns back to its original position, and the slack of the brake-rope is given out. This automatic take-up is applicable to all car-brakes which are operated by a chain or rope, extending throughout the whole length of the train.

We disclaim everything shown and described in the patent of Joseph Steger, dated October 27, 1868, No. 83,418; but having thus described our invention,

What we claim as new, and desire to secure by Letters Patent, is—

1. Giving to the friction-plate or bar H, a double-wedge shape from the centre towards its ends, substantially as shown and described.

2. The friction-plate or bar H, when the same is arranged, in combination with levers to be pushed and pulled, substantially as and for the purpose set forth.

3. The automatic take-up M, in combination with the buffer or coupling N, and brake-rope or chain, G, substantially as and for the purpose set forth.

BENJ. TATHAM.
JOSEPH STEGER.
